CLAIM

The ornamental design for a beverage bottle as shown and described.

DESCRIPTION

The patent or application file contains at least one drawing executed in color. Copies of this patent or patent application publication with color drawing(s) will be provided by the Office upon request and payment of the necessary fee.

Figure 1.1: shows a perspective view of a first embodiment of a beverage bottle, showing my new design

Figure 1.2: shows a left view thereof;

Figure 1.3: shows a front view thereof;

Figure 1.4: shows a right view thereof;

Figure 1.5: shows a bottom view thereof;

Figure 1.6: shows a top view thereof;

Figure 2.1: shows a perspective view of a second embodiment of a beverage bottle;

Figure 2.2: shows a left view of Figure 2.1;

(Continued)

Figure 2.3: shows a front view of Figure 2.1;
 Figure 2.4: shows a right view of Figure 2.1;
 Figure 2.5: shows a bottom view of Figure 2.1; and
 Figure 2.6: shows a top view of Figure 2.1
